UNITED STATES PATENT OFFICE.

WILLIAM R. KEATHLEY, OF ELLINGTON, MISSOURI.

SAFETY DEVICE FOR HORSE-DRAWN VEHICLES.

1,323,224.

Specification of Letters Patent. Patented Nov. 25, 1919.

Application filed March 13, 1918. Serial No. 222,160.

To all whom it may concern:

Be it known that I, WILLIAM R. KEATHLEY, a citizen of the United States, residing at Ellington, in the county of Reynolds and 5 State of Missouri, have invented certain new and useful Improvements in Safety Devices for Horse-Drawn Vehicles, of which the following is a specification.

This invention relates to new and useful 10 improvements in safety devices for horse drawn vehicles, and the primary object of the invention is to provide a means operable from the vehicle for releasing the team therefrom in case of a runaway so that the 15 danger to the occupants of the vehicle will be reduced to a minimum in case of accident.

Another object of the invention is to provide a safety device of this character which 20 comprises a double tree for light draft horse drawn vehicles that is releasably connected with the tongue of the vehicle, said releasing means being operable from the vehicle so that the double tree may be released in 25 case of a runaway or the like, to allow the team to become detached from the vehicle.

A further object of the invention is to provide a device of this character which is 30 easily and simply constructed, inexpensive to manufacture, and one which will be very efficient in operation.

With these and numerous other objects in view, my invention consists of the novel features of construction, combination and arrangement of parts which will be herein referred to and more particularly pointed out in the specification and claims.

In the accompanying drawings:

Figure 1 is a top plan view of the device, 40 Fig. 2 is a longitudinal section of the same, and

Fig. 3 is a transverse section showing the front of the doubletree.

In describing my invention, I shall refer 45 to the drawings in which similar reference characters designate corresponding parts throughout the several views.

The numeral 1 designates the tongue of the vehicle which is connected to the bow 2 50 that is secured to the front axle 3 of the same. This construction is of the conventional type ordinarily employed in light draft vehicles, that are drawn by horses such as buggies or the like, and my new and 55 improved safety attachment is adapted to be applied to this conventional construction.

The type of double tree 4 employed in this device is provided with upper and lower portions designated by the numerals 5 and 6, that are positioned above and below the tongue 1 of the double tree hence being slidably mounted thereon. The upper and lower portions of the double tree are provided with spacing guides comprising hollow tubes or rods 7, and are disposed in spaced relation intermediate the ends of the same, and which receive the tongue 1 therebetween. The top and bottom of the double tree are provided with alining openings intermediate the ends of the same for 70 a purpose to be hereinafter more fully described.

The releasing means employed in this device comprise a pair of upper and lower gripping jaws 8 and 9 which are hingedly 75 connected as shown at 10 with the tongue 1 at the top and bottom sides thereof adjacent the inner end of said tongue. These jaws 8 and 9 extend forwardly along the tongue, and their extremities are bent laterally as 80 shown at 11 to form hook portions adapted to be positioned in the openings in the top and bottom of the double tree. The jaws 8 and 9 are normally held into engagement with the double tree when the parts are positioned as is clearly shown in Fig. 2 of the drawings, by coiled springs 12 that are connected with the inner sides of said jaws and with the tongue. This spring connection however is adapted to be disengaged when 90 the double tree is released as will be herein-after more fully described.

The means for releasing the jaws or forcing them apart comprises an operating rod 13 that extends beneath the vehicle having 95 one end preferably connected with a foot lever or any other operating lever that is disposed adjacent the seat of the vehicle. This lever is not shown but it may be of any conventional type so that the rod 13 100 may be moved longitudinally when desired. The forward end of the operating rod 13 is disposed adjacent the inner end of the tongue and connecting the forward extremity thereof with the jaws 8 and 9 are a pair 105 of link members 14 which have loops 15 on their outer ends positioned around the jaws and engageable with the undersides thereof.

In operation, when the various parts of 110 the device are assembled as is clearly shown in Fig. 2 of the drawings, it is obvious that

the jaws 8 and 9 will be held into engagement with the double tree by the coiled springs 12. These springs tend to hold the said extremities of the jaws within the openings in the top and bottom of the double tree, and this engagement is sufficient to prevent any accidental disengagement. When it is desired to release the double tree in case of a runaway or the like, the operating rod 13 is moved forwardly said operation being controlled from the vehicle adjacent the driver's seat, and this forward movement of the rod 13 will consequently move the links 14 and as the links are in contact with the inner sides of the jaws 8 and 9 said jaws will be spread apart and their hooked extremities disengaged from the double tree. This will allow the double tree to slide along the tongue 1 and hence become disengaged from the vehicle. The spring connection owing to its loose nature will of course be released upon forward movement of the double tree.

This device forms a very simple and efficient safety attachment for light draft vehicles and one which readily permits the team to be disengaged from the vehicle in case of a runaway or the like. Although the attachment is not adapted for heavy draft vehicles, the need of a device of this character is most felt on light draft horse drawn vehicles and this safety attachment absolutely insures the safety of the driver in case of accident.

From the foregoing description taken in connection with the accompanying drawings, it is thought that a clear and comprehensive understanding of the construction, operation, and advantages of my invention may be had, and while I have shown and described the device as embodying a specific structure, I desire that it be under-

stood that such changes may be made in said structure as do not depart from the spirit and scope of the invention as claimed. 45

Having fully described my invention, what I claim as new, and desire to secure by Letters Patent, is:

1. In a device of the class described the combination with a vehicle tongue, a double tree slidably embracing said tongue intermediate its ends, and means for releasably connecting said double tree and the tongue. 50

2. In a device of the class described the combination with a vehicle tongue, a double tree having a portion intermediate its ends slidably embracing said tongue, and a releasable gripping member carried by said tongue and normally engaging the double tree. 55

3. In a device of the class described the combination with a vehicle tongue, a double tree slidably mounted intermediate its ends on said tongue, and a pair of spring tensioned gripping jaws carried by said tongue and normally engaging the double tree, and means for releasing said jaws operable from the vehicle. 60

4. In a device of the class described the combination with a vehicle tongue, a double tree slidably mounted intermediate its ends on said tongue, a pair of spring tensioned gripping jaws carried by said tongue and normally engaging the double tree, a longitudinally movable operating rod operable from the vehicle, and links connecting the extremity of said rod and the jaws whereby said jaws are adapted to be forced apart to release the double tree upon rearward movement of the operating rod. 70

In testimony whereof I affix my signature hereto.

WILLIAM R. KEATHLEY.
